UNITED STATES PATENT OFFICE.

COMTE YVES DE LA POËZE, OF ST.-FULGENT, FRANCE.

RADIATOR.

1,221,422.

Specification of Letters Patent.

Patented Apr. 1, 1917.

Application filed January 13, 1915. Serial No. 2,062.

To all whom it may concern:

Be it known that I, COMTE YVES DE LA POËZE, a citizen of the French Republic, residing at St.-Fulgent, Vendée, France, have 5 invented certain new and useful Improvements in Radiators, of which the following is a specification.

It has been already suggested to build radiators for central heating by arranging 10 side by side a certain number of vertical chambers in which the heating agent circulates. The said chambers are connected together at their upper and lower ends by means of parallel distributing pipes which 15 are connected to the general circuit of the installation. In order to increase the efficiency of such apparatus, and to produce automatically a circulation of air through the heating element, there have been arranged, 20 on the lateral walls of the said chambers, inclined conducting ribs, formed on the said walls as inclined ribs which, while acting as radiating ribs, offered the further advantage of receiving the heating fluid, and consequently 25 of increasing the exchange of heat. Again, in order to increase the efficiency of such apparatus, it has been proposed to act on the circulation of the heating fluid in the chambers themselves. To that end, the said 30 chambers, whether combined with inclined conducting ribs, or not, are constituted respectively by series of superposed quadrangular chambers which communicate with each other at their corresponding apices, so 35 as to force the current of fluid to undergo a series of contractions and expansions improving the exchange of heat.

In any installations of the kind described, 40 it is found however that there are numerous eddies in the circulation of air through the heating elements. As these eddies result in a loss of head and unfavorably affect the contact of the fluid to be heated, with the radiating walls, one would think that it would 45 be still further possible to increase the efficiency of the radiators described, by improving the circulation of air between the vertical walls of the chambers and the oblique partitions coöperating with the latter. In 50 order to do this, it must be borne in mind that the two main causes interfering with normal circulation of air and producing eddies, are the disturbances caused, firstly, in the flow of each fluid current between two 55 parallel oblique walls belonging to adjoining chambers, and secondly, in the circulation of

the various currents, externally of the radiating body. In fact, as the air progresses between the parallel walls of the chambers, in order to pass from the lowest inlet section 60 comprised between two inclined partitions, to the opposite discharge section, there takes place an increase of its volume, owing to the expansion produced by the increase of its temperature. But as the inclined partitions 65 are parallel, the fluid, on its way to the outlet openings, is exposed to a counter-pressure which retards its escape and which, by causing an expansion, produces eddies outside the apparatus. On the other hand, as the 70 inclined partitions are limited to one and the same vertical plane, it will be understood that each current of hot air escaping from each of the conduits formed between the pairs of inclined partitions, is interfered 75 with, and interferes with the circulation of other currents, as all the latter have the tendency to rise vertically by sliding along the rear partition of the radiator. There is therefore still a production of eddies interfering with the normal automatic circulation 80 of air in the room to be heated, and through the radiating elements.

This invention relates to a method by which the disadvantages are removed by 85 rendering more regular the circulation of air in the radiators which are constituted by vertical chambers, in the lateral walls of which are provided inclined ribs forming guide partitions. This method mainly consists in each chamber being made in the shape of a triangle, instead of a quadrangle, and in the ribs being differently inclined relatively to the horizontal. In that way, the cross-section of the circulation conduits 90 formed by the diverging partitions, gradually increases up to the outlet orifice corresponding to the inclined side of each triangular chamber, so that the said outlet orifices are moved horizontally relatively to each 100 other, so as to enable the fluid currents which escape and rise vertically, to follow parallel paths.

In the accompanying drawing a construction according to this invention is illustrated 105 Figure 1 showing in front elevation several elements, one of which is in section.

Fig. 2 is a corresponding side elevation, and

Fig. 3 shows the whole in perspective. 110 The radiator is constituted by fitting together several interchangeable elements, the

number of which depends on the volume of air to be heated. Each element is formed by hooking on circumferentially the depending edges of two stamped out sheet metal blanks

5 *a*, the surface of which has the shape of a rectangular triangle, the angles of which are rounded off. The small side forming the base, the right angle and the apex of the triangle, are provided respectively with a 10 collar *b* and *c* establishing communication between each chamber and that of the adjoining element. Oblique ribs *d*, with varying inclination relatively to the horizontal, are stamped out in the lateral walls of the 15 said chambers, and form, in addition to inner expansion chambers, contact surfaces between two elements, so that they form between them passages *e* widening upward. It will be seen that the cross-section of the 20 passages in question, owing to the divergence of the ribs, gradually increases from the cold air inlet to the hot air outlet, so that the fluid can freely expand without being exposed to counter-pressure producing losses of head or 25 eddies.

Moreover, as the discharge orifices terminate at the longest side of the vertical chambers, it will be seen that in the horizontal projection they are shifted relatively to each 30 other. The fluid currents escaping out of the corresponding passages *e* in order to rise afterward vertically, do not therefore interfere with each other, since, owing to the respective positions of the orifices enabling 35 them to escape, they can circulate parallel to each other. A sheet metal plate *f* forming a screen, could be arranged at the back of the radiator, in order to guide the whole of the said currents and prevent their coming out 40 and also to give the radiator the appearance

of an ordinary radiator. The upper portion *g* which provides outlet for the hot air, is provided with a grating or perforated partition.

What I claim as my invention and desire 45 to secure by Letters Patent is:—

1. In a radiator comprising several chambers arranged side by side, said chambers being of triangular shape the smallest side of which serves as a base for the radiator, 50 ribs of different inclination being provided on the exterior of the said walls, which ribs form between them air circulation conduits inclined on two opposite walls gradually widening in the direction of the outlet for 55 the hot air so as to present superposed outlet orifices.

2. In a radiator comprising several chambers arranged side by side, said chambers being of triangular shape the smallest side 60 of which serves as a base for the radiator, diverging oblique ribs with different inclinations being provided on the exterior of the said walls, which ribs form between them air circulation conduits inclined on two opposite walls widening gradually in the direction of the outlet for 65 the hot air, so as to present superposed outlet orifices and a vertical sheet of metal forming a screen arranged at the rear of the radiator with a 70 perforated upper portion for guiding the hot air outwardly.

In testimony whereof I have signed my name to this specification in the presence of two subscribing witnesses.
